UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed February 20, 1924, Serial No. 694,139. Renewed September 29, 1930.

My invention relates to mining machines.

An object of my invention is to provide an improved mining machine. Another object of my invention is to provide an improved mining machine of the so-called universal type. A further object of my invention is to provide a mining machine having improved and simplified adjusting means for the cutting mechanism forming a portion thereof. A still further object of my invention is to provide an improved mining machine having improved propulsion mechanism. Yet a further object of my invention is to provide an improved mining machine having cutting mechanism mounted in an improved manner whereby the same may be adjusted to insert a kerf in practically any plane in advance of the machine within the operating limits of the machine. Other objects and advantages of my invention will hereinafter more fully appear.

In the accompanying drawings I have shown for purposes of illustration one form which my invention may assume in practice.

In these drawings,—

Fig. 1 is a plan view of a mining machine constructed in accordance with the illustrative form of my invention, the cutter bar being partially broken away and shown in a position in alignment with the major dimension of the machine.

Fig. 2 is a side elevation of such a machine with parts similarly broken away.

Fig. 3 is a vertical section on a plane corresponding to the line 3—3 of Figs. 1 and 4 showing details of the bar adjusting mechanism.

Fig. 4 is a horizontal section on a plane corresponding to the line 4—4 of Fig. 3.

Fig. 5 is a section on an enlarged scale on a plane corresponding to the line 5—5 of Figs. 3 and 4.

Fig. 6 is a horizontal section showing portions of the truck driving mechanism,

a portion of the bar adjusting mechanism, transmission mechanism, etc.

Fig. 7 is a section approximately on a plane corresponding to the section line 7—7 of Fig. 6.

Fig. 8 is a detail sectional view on a plane corresponding to the line 8—8 of Fig. 6.

Fig. 9 is a sectional view on a plane corresponding to the section line 9—9 of Fig. 7.

Fig. 10 is a detail sectional view showing a locking mechanism.

Fig. 11 is another sectional view of this same mechanism, the view being taken on the broken line 11—11 of Fig. 10.

Fig. 12 is a section on the plane corresponding to the line 12—12 of Fig. 1.

Referring first to Figs. 1 and 2 and in order that a general concept of the illustrative form of the invention may be obtained as quickly as possible, it may be stated that the apparatus as a whole comprises a truck consisting of a truck body 1 mounted on wheels 2 and adapted to be propelled along a trackway 3, upon which truck is mounted mining mechanism generally designated M and including a motor casing 4, a gear housing 5, a cutter bar 6, and supporting and adjusting mechanism for the cutter bar generally designated 7, which mechanism I shall hereinafter more fully describe. In order to permit a moderate angular adjustment of the mining machine M as a whole about a transverse horizontal axis the following mechanism is provided.

It will be observed that the mining machine M is supported upon a platform 8 which is composed of a pair of parallel side members, herein angle irons 9, and suitable transverse portions, of which one is shown at 10. Each of the members 9 carries secured thereto projecting bearing members 11 which are adapted to seat upon and cooperate with projecting cylindrical members 12 bolted as at 13 to the lateral portions 14 of the truck body 1. These members 12

have flattened portions 12' which rest upon the frame 14 so that the bolts do not have any tendency to shear. It will be noted that the members 11 are arranged at about the center of mass of the tiltable portions of the mining machine and that the members 12 are arranged between the truck wheels so that the mining machine may be readily tilted and will be well supported. For the purpose of effecting tilting of the mechanism M about the journal members 12, there is provided upon the truck frame in suitable journals 15 a transverse shaft 16 to which at opposite sides of the center thereof but closely adjacent each other there are secured a pair of similar arms 17 which are connected at their free ends by a bolt 18 upon which there are rotatably mounted rollers 19. These rollers are arranged in slots or guideways 20 formed in members 20' which are secured to the bottom of the machine mechanism itself. From Figs. 7 and 9 it will be noted that when the machine frame is in its horizontal position the arms 17 are not vertical but inclined so that on swinging movement of the shaft 16 and resultant swinging of the arms 17 the rollers 19 traveling within the slots 20 may cause a tilting movement of the machine frame as a whole. Within reasonable limits this tilting movement may be in either direction about the horizontal axis. For the purpose of rocking the shaft 16 and holding it in different angular positions, an arm 21 is secured by keying or in any other suitable manner to one end thereof and with this arm there cooperates arm swinging means comprising an arm engaging member 22, which is threaded throughout a considerable portion of its length as indicated at 23, supported in suitable horizontal guides 24 and adapted to be moved longitudinally upon rotation of a nut 25 which engages the threaded portion 23, which nut may be rotated by a hand operated ratchet and pawl mechanism 26. It is to be observed that depending upon the direction in which the nut 25 is turned, the arm 21, and so the arms 17, will be swung in opposite directions and the machine frame either tilted from horizontal or brought back to horizontal position, it being moreover observed that the guides 24 are rigidly connected to the frame 8 so that as tilting of the frame occurs and as movement of the arm 21 takes place, there will be no binding at the connection between the member 22 and the arm 21. The mechanism so far described in relation to the tilting devices is very closely similar to that disclosed in my application Ser. No. 573,149, filed July 6, 1922.

The motor casing 4 contains a motor (not shown) which is supplied with current through a reeling device 30 described in a previously filed application, the motor be-

ing herein reversible and provided with suitable controlling and reversing mechanism of any suitable construction. The motor as usual comprises an armature shaft which is herein designated 31 and this shaft 70 projects through the opposite ends of the motor casing 4 and operates to transmit power for the driving of the cutting mechanism, for the changing of position thereof and for the feeding of the machine as a 75 whole both during cutting and in running around a mine. The rear end of the armature shaft which is designated 32 is provided with a spur pinion 33 that meshes with a spur gear 34 keyed or otherwise 80 suitably secured to a horizontal longitudinally extending shaft 35 on which a worm 36 is arranged. The worm 36 meshes with and drives a worm wheel 37 mounted upon a transverse hollow shaft 38 and under the 85 control of a suitable friction controlling mechanism 39 of well known construction effects the drive of a driving sprocket 40 whose position is indicated in Figs. 1 and 2. It will be understood that this sprocket 40 may be driven in either direction depending upon the direction of rotation of the shaft 31, or, at the will of an operator and on suitable manipulation of the friction mechanism 39, permitted to rotate when disconnected from the shaft 38. A suitable belt connection 41 driven from a portion of the friction mechanism described serves to effect drive of the reel 30, the drive of which reel is further controlled by a belt 100 tightener 42. This mechanism also corresponds to that described in my earlier filed application referred to above.

The forward end of the armature shaft 31 is designated 45 and has connected thereto a sleeve 46 which is provided with a driving pinion 47. This pinion meshes with and drives a larger spur gear 48 which is carried upon a horizontal longitudinally extending shaft 49 which is suitably journaled as at 110 50 and 51 in the machine frame. At its forward end the shaft 49 carries a bevel pinion 52 which meshes with and drives a pair of coaxial oppositely facing bevel gears 53, 54. The latter are connectible by friction clutch 115 mechanisms of a well known form, which are generally designated 55 and 56, alternatively with a transverse horizontal shaft 57. A suitable shipper mechanism 58 carried by a hollow horizontal transverse sleeve 120 59 is normally held in neutral positions by oppositely acting springs 60 arranged between adjustable collars 61 and collars 62 engaging the ends of the sleeve 59. Within the sleeve 59 is a shaft 63 having shoulders 64 adapted to engage the collars 62 on longitudinal movement and to free the sleeve of the influence of one or the other of the springs 60. The shaft 63 is movable by the interaction of a rack 65 and gear segment 125 66.

66 in a manner to effect control of the clutches 55 and 56 and so the alternate connection or the complete disconnection of the gears 53 and 54 from the shaft 57. The 5 segment 66 is controlled by a hand lever 67 upon the top of the gear housing 5, which lever has forward and reverse operating positions in which it may be locked by any suitable means. It will be observed that the 10 loading of the friction clutches is by the springs 60 and these may be so adjusted as to cause slipping of the frictions to occur at any desired load so as to prevent over-loading of the motor or breakage of the gear- 15 ing. The shaft 57 is provided with a worm 68 which meshes with a worm wheel 69 upon a collar 70 which is keyed to a horizontal longitudinally extending shaft 71 arranged below and to one side of the axis of the ar- 20 mature shaft. Obviously reverse rotation of the shaft 71 is effected by reverse rotation of the shaft 57. The shaft 71 is supported in suitable bearings 72 and 73 formed in the gear casing 5 and the shaft carries 25 adjacent the latter of these bearings, and to the rear of the worm wheel 69, a worm 75 which meshes with and drives a worm wheel 76 rotatably mounted on a transverse horizontal shaft 77 journaled as at 78, 78' 30 in the gear casing 5. Suitable clutch mechanism indicated by 79 is provided for the purpose of connecting the worm wheel 76 to the shaft 77, this in the illustrative form shown being of the so-called Fellows type 35 of clutch. The shaft 77 projects through the side wall of the gear casing 5 and has geared thereto a driving sprocket 80. The clutch mechanism 79 is operable by a handle 40 disposed upon the top of the gear casing 45 and adapted to be secured in either of its positions by any suitable means. This mechanism just described is also substantially the same as that described in my earlier filed application mentioned above.

45 The truck wheels 2 are mounted upon axles 82 which extend completely across the truck body 1. The rear axle 82 is provided with a pair of sprocket wheels numbered respectively 83 and 84, the wheel 83 being 50 arranged at that side of the truck body at which the sprockets 40 and 80 are to be found. The forward axle 82 has secured thereto a sprocket 85 and a chain 86 cooper- 55 ating with the sprockets 84 and 85 connects the axles for simultaneous rotation in the same direction. For the purpose of maintaining the chain 86 in proper tension, an eccentrically mounted adjustable idler sprocket 87 of the type described in my 60 above mentioned application is provided. A driving chain 88 passes, as best shown by dotted lines in Fig. 2, around the sprockets 40 and 80 and around the sprocket 83 upon the rear axle 82, it being also observed from 65 Fig. 1 that the chain passes around a fur- ther sprocket 89 which is best shown in Fig. 9 and which is adjustable in position to vary the tension of the chain. The adjusting mechanism for this sprocket which presents certain features of novelty over my prior application, is of such nature as to permit adjustment of two types, one an initial adjustment to provide a proper chain tension and the other an adjustment which accompanies a tilting of the mechanism so as to keep the 70 chain under proper tension notwithstanding a tilting about the axis of the members 12. The sprocket 89 is journaled upon a shoul- 75 dered sleeve 90 which cooperates with a circular member 91 having a flange 92 clamp- 80 ing a stationary circular bearing member 93 carried upon the extremity of an arm 94. A stud 95 is threaded into the member 91 and the nut 96 is adapted to connect the parts in such a manner as to hold the sprocket 85 in any desired position. As it will be noted that the portion of the member 90 about which the sprocket 89 is rotatable is not concentric with the portion of the member 90 which is rotatable in the member 93, 90 it will be evident that the member 90 may so move as to provide more slack or to tighten the chain 88. The arm 94 is mounted upon the shaft 16 at the opposite end of the latter from the arm 21 and upon tilt- 95 ing of this shaft in a direction to raise the right hand end of the mechanism in Fig. 1, it will be observed that the arm 94 swings in such direction as to cause a slackening in the chain thereby maintaining the tension of 100 the chain substantially constant. A reverse effect of course accompanies an opposite tilt- 105 ing.

It seems advisable to set forth the operation of the mechanism so far described before providing any further description of the structure. It will be evident that during running around a mine it is immaterial whether the cutter chain runs at all or what direction it runs in, although it is preferable that it does not run at all, as is the case herein by reason of structure which will shortly be described. It is accordingly possible to reverse the motor and so to reverse the direction of rotation of the armature shaft 31 without in any way interfering with the operation of the mechanism. Accord- 110 ingly the friction clutch mechanism 39 will suffice to control the connection of the rear end of the armature shaft by way of the pinion 33, gear 34, worm 36, worm wheel 37 and shaft 38 with the driving sprocket 40 and so effect the running of the machine at a relatively high rate of speed about the mine. When it is desired to cut and feed the machine during cutting it is obvious that unless the cutter bits are to be shifted, the motor must run continuously in one direction unless, of course, reversing mechanism 115 with its additional complication is provid- 120 125 130

ed in the cutter chain driving train. Accordingly it must be possible, if sumping and withdrawing cuts are to be made, to reverse the direction of movement of the machine 5 without reversing the motor. For this reason I have provided reversible driving mechanism including the clutches 55 and 56, etc. and so am able to reverse the direction of rotation of the driving sprocket 80 at will 10 while maintaining the direction of rotation of the armature shaft 31 unchanged. If it is desired to effect bodily movement of the machine in one direction, then to maintain it stationary, and then to move it bodily in 15 the opposite direction, the steps necessary will include the operation of whichever one of the clutches 55 or 56 are to be thrown into engagement to effect the desired initial direction of feed, thereafter to disconnect both 20 of the frictions 55 and 56 while leaving the clutch mechanism 79 engaged (in which position of the parts the worms will lock the sprocket 80 against rotation) and then to engage the other of the clutches 55 and 56. 25 By reason of the plurality of worms, etc., it will be evident that the speed during cutting will be much less than during running about the mine. As the mechanism so far described is, with the exceptions noted, very 30 closely similar to the disclosure of my earlier filed application, it is believed that it is not necessary to go into greater detail in the description of the mode of operation of these parts. 35 The cutting mechanism includes the cutter bar and driving mechanism for the chain thereof, and means for effecting two different types of bodily adjustment of the cutter bar, one the rotation of the bar bodily about 40 a horizontal axis, and the other movement of the bar towards and from that axis rectilinearly, and mechanism for swinging the bar is also provided. For the purpose of supporting the cutting mechanism there is 45 provided upon the front end of the frame section 5 an annular seat 100 to which is secured an annular sleeve or retaining and bearing member 101 having an inwardly directed flange 102. Between the flange and 50 the shoulder 103 also formed upon the front end of the frame member 5, there is rotatably secured a sleeve 104 which is fastened by bolts 105 or in any other suitable manner to a projecting neck member 106, it being possible 55 to construe the member 106 and the sleeve 104 as together making up a neck if desired. The member 106 also has herein formed integral with it a pair of parallel portions 107 to which guideways hereinafter 60 described are secured, these members being connected adjacent their lower ends by a transverse web 108 and being connected by webs 109 to the right hand end of the neck member 106 while curved webs 110 serve to 65 connect them with the generally circular

member 111 which will be more fully described. To the members 107 there are bolted trough-like guideways 112 in which there are slideable cross-head members 113, these being secured to members 114 which are 70 bolted or otherwise suitably fastened to a cutter bar supporting frame 115. It will be observed that the member 115 has secured to the lower end thereof an annulus 116 which together with an annular shoulder 117 75 upon the member 115 provides a guideway for a large internal gear 118 to which there is secured as at 119 a casting 120 which carries the cutter bar 6 of the machine and which also constitutes a guard for the cutter 80 bits.

For the purpose of effecting rotation of the neck 106 and with it bodily movement of the cutter bar about the axis of the armature shaft, I have provided means driven 85 from the shaft 71 and consisting of a spur gear element 121 coaxial with which there is a second spur gear element 122 held as at 123 to a shaft 124 which is journaled at its rear end 125 within a recess 126 in the shaft 90 71 while at its forward end it carries a spur pinion 127 which meshes with the internal gear 104, the front end of the shaft 124 being journaled as at 126' in the front end of the gear casing. A clutch sleeve 128 is movable 95 in opposite directions by a shipper mechanism 129 whose operating handle 130 is arranged upon the top of the casing 5. By oscillation of the handle 130 it will be evident that the clutch element 128 may be 100 moved in such manner as to connect the gears 121 and 122, which will cause the shafts 71 and 124 to rotate together and so will cause rotation of the internal gear 104 and of the neck 106. This will cause bodily 105 movement of the cutter bar about the axis of the armature shaft extended. It will be noted that for the purpose of locking the neck in different adjusted positions there is provided a locking rack element 131 carried 110 upon and pivoting about a shaft 131' to which there is secured a member 132 which carries upon a pivot 133 a hand lever 134, the hand lever being capable of swinging movement transverse to the plane of rotation 115 of the member 132 so as to release a latch 135 from notches 136, there being a spring 137 which operates, however, normally to hold the latch in the notch. 120 To recapitulate, it may be stated that to effect rotation of the neck and so bodily movement of the cutter bar about the extended axis of the armature shaft, the locking rack 131 will be moved out of engagement with the internal gear 104 by movement of the hand lever 134 first to release the latch and thereafter to swing the element 130 out of engagement with the teeth of the internal gear and thereafter, the clutch member 128 connecting the shaft 124 to the shaft 130 125

71 so that the pinion 127 will rotate the internal gear 104 and with it the neck, the proper friction clutch 55 or 56 may be engaged to cause the desired movement. When 5 the desired position of adjustment is reached, the friction clutch will be unloaded and before the clutch 128 is disengaged from the member 121 the member 131 will be reengaged with the teeth of the internal 10 gear 104.

As a preliminary to a further description of the cutting mechanism, it should be observed that a shaft 140 is arranged in alignment with the armature shaft 31 and 15 is keyed within a member 140' which is non-rotatably secured to the member 46 carrying the driving pinion 47, the parts constituting a flexible coupling. This shaft 140 extends through the neck and at its 20 forward end carries a bevel pinion 141 which meshes with and is adapted to drive a large bevel gear 142 rotating upon a vertical axis. The gear 142 is enclosed in a housing including the portion 111 integral 25 with the neck and a cover member 143, suitable bearings 144 being provided, and within these bearings there being journaled a tubular member 145 to which the gear 142 is connected by a spider member 146 which 30 is keyed as well as bolted to the member 145. At its lower end the member 145 carries a series of threads 147 which make up a nut and cooperating with this nut is a long heavy screw 148. This screw at its 35 lower end is provided with a reduced portion 149 and carries at its extreme lower extremity a cutter chain driving sprocket 150 which is, however, rotatably mounted with respect to the portion 149, being held, 40 however, against downward movement with respect to the latter by a member 151. Just above the reduced portion 149 there is a collar 152 which may be left in the machining of the screw member 148 and this 45 collar engages one element 153 of a large ball thrust bearing, while upon the other element 154 of this bearing there rests an annulus secured to a cover member 155 which goes, together with the member 115 and 50 a closure and journal member 156, to make up a casing housing the mechanism for driving the cutter bar and swinging the same. The lower side of the member 153 is engaged by a shoulder 174' on a member 174, 55 hereinafter more fully described, which member is held against longitudinal movement relative to the portion 149 by engagement with a split or two part collar 152' engaged in a groove in the portion 149. The 60 lower part of the element 154 is held by suitable holding and locking means 154' in fixed space relation to the housing 155. As a result of this construction, the weight of the parts is suspended from the screw 65 whether the position is as shown or inverted.

A cover plate 157 surrounds the screw and is provided with a recess 158 in which a felt ring or other means for preventing the access of dirt is housed.

Referring to the mechanism within the 70 casing made up of the parts 11 and 143, it will be noted that within the member 145 is a sleeve 160 provided with inwardly projecting splines 161 which engage in grooves 162 extending longitudinally of the 75 member 148 so that so long as the member 160 is held against rotation the screw 148 is also maintained stationary in so far as rotation upon its axis is concerned. The member 160 carries at its upper end a member 163 splined thereto as at 164 and having spur teeth 165 projecting about its periphery. The member 145 has corresponding spur teeth 166 and a third set of similar spur teeth 167 is carried upon a depending portion of a member 168 secured to the member 143. A clutch member 169 having slots adapted to cooperate with the teeth 165, 166 and 167 is vertically reciprocable at the upper end of the member 160 and 80 when in the position shown in Fig. 3 serves to connect neither the teeth 166 nor the teeth 167 to the teeth 165, but on downward movement connects the teeth 165 and 166 in such manner that the screw and the nut 90 rotate together while on upward movement it connects the teeth 165 and 167 so that the member 160, being clutched to a member which is stationary, is held against rotation and prevents rotation of the screw with the 100 result that rotation of the nut 147 due to rotation of the gear 142 will be accompanied by longitudinal movement of the member 148 in one direction or the other depending upon the direction of rotation of the gear 105 142.

Surrounding the neck portion of the reduced portion 149 of the member 148 and also surrounding the upper portion of a sleeve 170 which is integral with the driving 110 sprocket 150 is a sleeve member 171 having radially projecting clutch teeth 172 with which a clutch member 173 cooperates. The member 171 is connected in non-rotative relation to the cutter chain driving sprocket 115 150. Surrounding the uppermost portion of the reduced portion 149 is a sleeve 174 which carries at its lower end a series of teeth 175 similar in dimension and arrangement to the teeth 172 upon the sleeve 171. On upward movement of the clutch from the position shown in Fig. 3, it will be evident that the teeth 172 and 175 will be connected together and so since the sleeve 174 is connected by a key 176 to the portion 149 of the 120 member 148, rotation of the member 148 will effect cutter chain drive. On resumption of the position shown in Fig. 3, the cutter chain driving sprocket may remain stationary, notwithstanding rotation of the 130 125 member 148.

member 148. A clutch shipper 179 is pivoted at 180 in the lower housing mentioned above and has a rocker arm 181 with which a lever 182 cooperates for the purpose of effecting raising and lowering of the clutch member 173. The arm 182 is keyed to a shaft 184 which projects laterally through the casing and a lever 185 shown in Fig. 4 is provided to effect the movements of the clutch member. Suitable means 186 is provided for the purpose of controlling the movement of the clutch 169.

Surrounding the sleeve 174 and keyed thereto as at 188 is a spur gear 189 which will be noted in Fig. 4 to mesh with a pair of spur gears 190 and 191 arranged on vertical shafts and connected to vertically disposed oppositely threaded worms 192, 193 respectively. These worms in turn are connected in driving relation with a pair of worm wheels 194 and 195 which are arranged as is indicated in the case of the worm wheel 194 in Fig. 5, upon a transversely extending shaft 196. The shaft 196 carries rigidly secured thereto a worm 197 which meshes with a worm wheel 198 upon a vertical shaft 199 journaled in the frame and carrying at its lower end a pinion 200 which meshes with the internal gear 118. It will be obvious that rotation of the worm wheel 199 and so of the pinion 200 will effect bar swing. At this point it should be noted that the lead of the worms 192 and 193 is different as well as the threads being opposite, these being proportioned to provide fast bar swing for positioning and slow bar swing for cutting.

As a result of this construction when the worm wheel 194 is acting as the driving worm for the shaft 196, bar swing will take place at one rate in one direction while when the worm wheel 195 is the driving element, bar swing will take place at a different rate in the opposite direction, the swing during cutting being at a substantially slower rate than the swing during positioning of the bar. For the purpose of connecting the worm 194 to the shaft 196, mechanism is provided as shown in Fig. 5, and it will be understood that corresponding mechanism is provided for connecting the worm 195 to the shaft 196. It will be observed that a friction clutch housing member 205 is keyed to a reduced portion of the shaft 196 as by a key 206. Within this housing and connected thereto by splines 207 are a series of friction discs 208. The worm wheel 194 is bolted to a hub or sleeve member 209 which carries a series of splines 210 with which a series of friction discs 211 are connected, these discs being arranged in alternate relation with the discs 208. It will be evident that when the discs 208 and 211 are pressed into engagement with each other, there will be a clutching of the worm wheel 194 and the

shaft 196. For the purpose of pressing the parts into engagement a series of friction applying fingers 212 are arranged through openings 213 in the housing member 205. Coaxial with the shaft 196 is a member 215 having a flange 216 adapted to engage the fingers 212 and cause them to force the friction discs into a tight engagement with each other. The member 215 is provided with coaxial portions 217, 218 the latter of which is the smaller and also internally threaded. Threaded into the portion 218 is a member 219 and this member carries a shoulder 220 against which an annulus 221 forming a part of a ball bearing rests. Between the member 221 and a corresponding member 222 a series of balls 223 are arranged. The member 222 engages a sleeve like collar member 224 which is slidable along the reduced portion 218 of the member 215. Between the member 224 and the portion 216 and surrounding the portion 217 of the member 215 is a heavy spring which is held under a predetermined compression by the threaded engagement of the member 219 with the portion 218 of the member 215. A shaft 230 extends completely through a bore within the member 196 and is provided with handles 231 and 232 at its opposite ends. Pinned to the shaft 230 at either end are members 233 which are threaded into openings 234 in the housing, these members being so threaded that upon rotation of the shaft 230 in one direction both are moved in the same direction.

The mode of operation of this clutching mechanism will be readily apparent from the description given. Assume that the handle 231 is turned in such direction as to cause the member 233 to move toward the left. This will exert pressure upon the member 221 and sufficient pressure can be exerted upon this member to cause the spring to yield, but thereafter the further compression of the spring will not produce a very substantial increase in pressure upon the friction discs so that there is provided a certain fairly definite normal load for the clutches.

The general mode of operation of the machine may now be still further described. The manner of controlling the propulsion mechanism has been described in some detail already, but brief reference to this is desirable in connection with the further description of the operation of the machine as a whole. Let it be supposed that the machine is at some distance from the point where it is desired to insert a kerf. At such a time, in view of the fact that the machine has to run around the mine, the cutter bar and its supporting parts will be raised a substantial distance above the track so that there may be no interference in going down hill or starting to go up hill. It will be

understood that at this time the machine is being propelled by the sprocket 40 under the control of the frictional mechanism 39. When, however, the machine reaches a point 5 where it is desirable to insert a kerf, the machine will be stopped by unloading the friction mechanism 39, and then the bar will be adjusted to the position in which the kerf is desired. Let it be assumed for the 10 purpose of illustrating the adjustments that it is desired to make the cut near the roof and at a distance above the axis of the armature shaft greater than the distance from the shaft axis in which the bar is carried 15 during running around the mine. The change in distance of the bar from the axial line of the armature shaft or the bodily movement of the bar about this axis may either be made first, but let it be assumed 20 that it is decided to move the bar to the desired distance from the axial line of the armature shaft first. To accomplish this, the clutch sleeve 169 will be thrown upward so that the teeth 165, 167 will be locked together 25 and as a result the member 160 will be held against rotation and so prevent rotation of the screw 148. Rotation of the nut 147 in the proper direction will move the cutter bar away from the axis of the armature shaft. The motor will accordingly be caused to rotate in the proper direction by proper actuation of any usual suitable reverse switch which, as it may be of any type, is not illustrated herein. After the bar 30 has been moved to the desired distance from the axis of the armature shaft, the clutch 169 will be thrown to its lower position and the clutch 128 will be thrown to connect the teeth 121 and 122, the handle 134 moved to 35 release the lock element 131, and the clutch 55 or 56 engaged to cause bodily adjustment of the bar about the neck axis. When the machine reaches the proper position the friction clutch will be unloaded, the handle 134 40 will be moved to throw in the lock, and the clutch element 122 will be thrown back to the position shown in Fig. 8. The bar will then be in the desired plane for making the kerf. The handle 231 or 232, whichever happens 45 to be the more conveniently located, will then be grasped by the operator and turned in the proper direction to cause worm wheel 195 to be connected to the shaft 196 and the bar will then be swung rapidly in a 50 counterclockwise direction. When the desired position is reached, the handle 231 or 232 will be turned to disconnect the bar swinging means and the bar will be held locked by the worm 197. The machine feeding mechanism which is used during cutting 55 will then be brought into operation by manipulation of the lever 81 and the machine will be fed into the coal, the cutter chain being driven at this time by reason of the 60 fact that the clutch member 173 will be

thrown upward to engage the teeth 172 and 175. When the desired depth is reached, the lever 81 will be thrown to neutral position and the machine stopped. The other worm wheel 194 will then be clutched to the shaft 70 196 by suitable manipulation of the shaft 230 and the bar will be caused to make a swinging cut, this swinging cut being effected while the bar is moving more slowly by reason of the smaller lead of the worm 75 which is then operated. At the end of the swinging cut the shaft 230 will again be moved to a position to unload both clutches which control the worm wheels 194 and 195 and the lever 81 manipulated to cause the 80 machine to be backed out of the coal while making a withdrawing cut, it being understood that during cutting the sprocket 80 is the one which effects propulsion of the machine. After the completion of the cut, it 85 will be evident that the bar may be moved to any desired position for transport and the machine propelled around the mine by the proper manipulation of the controlling mechanisms. As, however, these operations 90 will be readily understood from what has already been described, it seems unnecessary to describe them in any detail.

While I have in this application specifically described one form which my invention 95 may assume in practice, it will be understood that this form of the same is shown for purposes of illustration and that the invention may be modified and embodied in various other forms without departing from its 100 spirit or the scope of the appended claims.

What I claim as new and desire to secure by Letters Patent is:

1. In a mining machine, a cutter bar provided with orbitally moving cutting elements, a screw rotatable on an axis perpendicular thereto and constituting means for effecting orbital movement of said cutting elements, and means adapted to cooperate with said screw to effect movement of said 105 bar bodily by power in a direction in which said screw extends.

2. In a mining machine, a cutter bar, a screw rotatable on an axis perpendicular thereto and constituting bar actuating 110 means, and means adapted to cooperate with said screw to effect movement of said screw and of said bar bodily by power in a direction in which said screw extends.

3. In a mining machine, a cutter chain 115 carrying cutter bar, a member rotatable on an axis perpendicular thereto and constituting chain actuating means, and means adapted to cooperate directly therewith at the will of an operator to move said bar by 120 power rectilinearly in the direction in which the axis of said member extends throughout such movement.

4. In a mining machine, a cutter chain 125 carrying cutter bar, a member rotatable on 130

- an axis perpendicular thereto and constituting chain actuating means, and means adapted to cooperate directly with said member at the will of an operator to move said member and said bar by power rectilinearly in the direction in which said member extends throughout such movement. 5
5. In a mining machine, a cutter chain carrying cutter bar, a screw rotatable on an axis perpendicular thereto and constituting chain actuating means, and means adapted to cooperate directly therewith at the will of an operator to move said bar by power in the direction in which said screw extends. 10
- 10 6. In a mining machine, a cutter chain carrying cutter bar, a screw rotatable on an axis perpendicular thereto and constituting chain actuating means, and means adapted to cooperate directly therewith at the will of an operator to move said screw and said bar by power in the direction in which said screw extends. 15
- 15 7. In a mining machine, a cutter bar, actuating means therefor including a driving shaft, and means for adjusting the same and said bar by power rectilinearly to different positions parallel to lines parallel to their original positions including cooperating means coaxial with said shaft. 20
- 20 8. In a mining machine, a cutter bar, a bar actuating element, a screw coaxial therewith and driving the same, and nut means cooperable with said screw to effect adjustment by power of said bar to a different position parallel to its first position. 25
- 25 9. In a mining machine, a cutter bar, a bar actuating element, a screw coaxial therewith and driving the same, and nut means cooperable with said screw to effect adjustment of said bar to a different position parallel to its first position, said screw being rotatable with said nut means or adapted to be held stationary to cause such adjustment by power. 30
- 30 10. In a mining machine, a cutter bar, a bar actuating element, a screw coaxial therewith and driving the same, a nut, said screw being rotatable with said nut or adapted to be held stationary, and means for holding said screw stationary. 35
- 35 11. In a mining machine, a cutter bar, a bar actuating element, a screw coaxial therewith and driving the same, a nut, said screw being adapted to be held in non-rotatable relation with said nut or to be held stationary, and means for holding said screw stationary. 40
- 40 12. In a mining machine, a cutter bar, a bar actuating element, a screw coaxial therewith and driving the same, a neck, members cooperating with said screw to support and at the will of the operator move said tool on said neck at right angles to and toward and from the axial line of said mechanism in any position thereof about said 45
- neck, and means including means extending along the axial line of said neck for actuating said screw. 50
- 50 13. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft extending between said first mentioned and second mentioned shafts, worm driving means between said transverse shaft and said second mentioned shaft, and plural set worm driving means between said first mentioned shaft and said transverse shaft. 55
- 55 14. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft between said first and second mentioned shafts, worm driving means between said transverse shaft and said second mentioned shaft, and fast and slow worm driving means comprising separate fast and slow worms between said first mentioned 60
- 60 shaft and said transverse shaft. 65
- 65 15. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft between said first mentioned and second mentioned shafts, worm driving means between said transverse shaft and said second mentioned shaft, and worm driving means between said first mentioned shaft and said transverse shaft, including worms rotating on axes parallel to and at opposite sides of said first mentioned shaft and worm wheels coaxial with said transverse shaft. 70
- 70 16. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means selectively connected to said bar and to said second mentioned shaft whereby on rotation of said second mentioned shaft said bar is swung, a transverse shaft 75
- 75 17. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft 80
- 80 18. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft 85
- 85 19. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft 90
- 90 20. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft 95
- 95 21. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft 100
- 100 22. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft 105
- 105 23. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft 110
- 110 24. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft 115
- 115 25. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft 120
- 120 26. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means selectively connected to said bar and to said second mentioned shaft whereby on rotation of said second mentioned shaft said bar is swung, a transverse shaft 125
- 125 27. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft 130

- shaft between said first mentioned and second mentioned shafts, worm driving means between said transverse shaft and said second mentioned shaft, and worm driving means between said first mentioned shaft and said transverse shaft including worms of different pitch rotating on axes parallel to and at opposite sides of said first mentioned shaft and worm wheels coaxial with said transverse shaft. 10
17. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means operatively connected to said bar and to said second mentioned shaft whereby on rotation of said second mentioned shaft said bar is swung, a transverse shaft between said first mentioned and second mentioned shafts, worm driving means between said transverse shaft and said second mentioned shaft, and worm driving means between said first mentioned shaft and said transverse shaft including worms rotating on axes parallel to and at opposite sides of said first mentioned shaft and worm wheels coaxial with said transverse shaft, 20 and friction means for connecting either of said worm wheels to said shaft. 25
18. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft between said first mentioned and second mentioned shafts, worm driving means between said transverse shaft and said second mentioned shaft, and worm driving means between said first mentioned shaft and said transverse shaft including worms of different pitch rotating on axes parallel to and at opposite sides of said first mentioned shaft and worm wheels coaxial with said transverse shaft, and friction means having substantially limited power transmitting capacity arranged between said worm wheels and said shaft. 30
19. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means operatively connected to said bar and to said second mentioned shaft whereby on rotation of said second mentioned shaft said bar is swung, a transverse shaft between said first mentioned and sec- 35
- ond mentioned shafts, worm driving means between said transverse shaft and said second mentioned shaft, and worm driving means between said first mentioned shaft and said transverse shaft including worms rotating on axes of different pitch parallel to and at opposite sides of said first mentioned shaft and worm wheels coaxial with said transverse shaft, and friction means arranged between said worm wheels and said shaft, and means coaxial with said shaft for controlling the loading of said frictions. 40
20. In a mining machine, a bar, and bar swinging mechanism including a shaft perpendicular to the plane of swing of the bar arranged at the pivot of the bar, a second shaft arranged in fixed spaced relation to the bar and parallel to said first mentioned shaft, means respectively connected to said bar and to said second mentioned shaft whereby on rotation of said second mentioned shaft said bar is swung, a transverse shaft between said first mentioned and second mentioned shafts, worm driving means between said transverse shaft and said second mentioned shaft, and worm driving means between said transverse shaft and said second mentioned shaft including worms rotating on axes of different pitch parallel to and at opposite sides of said first mentioned shaft and worm wheels coaxial with said transverse shaft, and friction means arranged between said worm wheels and said shaft, and means coaxial with said shaft for controlling the loading of said frictions and including a shaft extending through said transverse shaft. 45
21. In a mining machine, the combination with a pivoted cutter bar and a driving motor therefor, of means for swinging said cutter bar in opposite directions at different speeds by power including a rotatable member to which said bar is connected, and means including parallel shafts parallel to the bar pivot and rotating at equal speeds operatively connectible in driving relation with said rotatable member to swing said bar at different speeds. 50
22. In a mining machine, the combination with a pivoted cutter bar and a driving motor therefor, of means for swinging said cutter bar in opposite directions at different speeds by power including a rotatable member to which said bar is connected, and means including parallel shafts parallel to the bar pivot and rotating at equal speeds, and different gear reductions driven thereby operatively connectible in driving relation with said rotatable member to swing said bar at different speeds. 55
23. In a mining machine, the combination with a pivoted cutter bar and a driving motor therefor, of means for swinging said cutter bar in opposite directions at different speeds by power including a rotatable mem- 60

ber by which said bar is carried, a driving member for said rotatable member rotating on an axis parallel to the axis of the latter, and means including parallel shafts parallel to the bar pivot and rotating at equal speeds 5 operatively connectible in driving relation with said rotatable member to swing said bar at different speeds.

24. In a mining machine, the combination 10 with a cutter bar and a driving motor therefor, of means for swinging said cutter bar in opposite directions at different speeds by power including a rotatable member by which said bar is carried, a driving member for said rotatable member rotating on an 15 axis parallel to the axis of the latter, and means including parallel shafts parallel to the axis of said driving member and rotating at equal speeds and different gear reductions driven thereby operatively connectible 20 in driving relation with said rotatable member to swing said bar at different speeds.

25. In a mining machine, the combination 25 with a cutter bar and a driving motor therefor, of means for swinging said cutter bar in opposite directions at different speeds by power including a rotatable member by which said bar is carried, a driving member for said rotatable member rotating on an 30 axis parallel to the axis of the latter, and means including parallel shafts parallel to the axis of said driving member and rotating at equal speeds operatively connectible 35 in driving relation with said rotatable member to swing said bar at different speeds, and means manually operable to effect such connections but not simultaneously.

26. In a mining machine, the combination 40 with a cutter bar and a driving motor therefor, of means for swinging said cutter bar in opposite directions at different speeds by power including a rotatable member by which said bar is carried, a driving member for said rotatable member rotating on an 45 axis parallel to the axis of the latter, and means including parallel shafts parallel to the axis of said driving member and rotating at equal speeds and different gear reductions driven thereby operatively connectible 50 in driving relation with said rotatable member to swing said bar at different speeds, and means manually operable to effect such connections but not simultaneously.

27. In a mining machine, the combination 55 with a cutter bar and a driving motor therefor, of means for swinging said cutter bar in opposite directions at different speeds by power including a rotatable member by 60 which said bar is carried, a driving member for said rotatable member rotating on an axis parallel to the axis of the latter, and means including parallel shafts parallel to the axis of said driving member and rotating 65 at equal speeds operatively connectible

in driving relation with said rotatable member to swing said bar at different speeds, and means manually operable to effect such connections but not simultaneously, said means being provided with operating elements arranged at either side of the cutter bar in the median position of the latter. 70

28. In a mining machine, the combination 75 with a cutter bar and a driving motor therefor, of means for swinging said cutter bar in opposite directions at different speeds by power including a rotatable member by which said bar is carried, a driving member for said rotatable member rotating on an axis parallel to the axis of the latter, and means including parallel shafts parallel to the axis of said driving member and rotating at equal speeds and different gear reductions driven thereby operatively connectible 80 in driving relation with said rotatable member to swing said bar at different speeds, and means manually operable to effect such connections but not simultaneously, said means being provided with operating elements arranged at either side of the cutter bar. 85

29. In a mining machine, the combination 90 with a machine frame, a pivoted plane cutter and a driving motor therefor, of means for supporting said cutter on said frame 95 permitting angular bodily adjustment thereof of about an axis extending longitudinally of said frame, said cutter being adapted to cut in planes parallel to the axis of said adjustment and being adjustable by power 100 from said motor rectilinearly toward and from said axis while its plane remains perpendicular to the path of rectilinear adjustment and being swingable at different rates in opposite directions about its pivot. 105

30. In a mining apparatus, a wheel mounted truck, a mining machine on said truck, said truck including a portion arranged to permit tilting of said mining machine relative to another portion of said truck, a chain drive for said truck including a chain loop operatively connected to at least one truck wheel, a plurality of driving sprockets projecting laterally from said machine and engaging with said loop, and means for tightening and loosening said chain carried, independently of the tilting portion, directly by the portion of said truck which does not tilt. 110

31. In a mining apparatus, a wheel mounted truck, a mining machine on said truck, means permitting tilting of said mining machine relative to a portion of said truck, a chain drive for said truck including a chain loop operatively connected to at least one truck wheel, a plurality of driving sprockets projecting laterally from said machine and engaging with said loop, and means for tightening and loosening said chain including a rotatably mounted chain 115 120 125 130

guiding element and means for supporting the same for swinging movement relative to said truck about an axis which is different from the axis of tilt of said machine 5 and which axis remains stationary during machine tilting.

32. In a mining apparatus, a wheel mounted truck, a mining machine on said truck, means permitting tilting of said mining 10 machine relative to a portion of said truck, a chain drive for said truck including a chain loop operatively connected to at least one truck wheel, a plurality of driving sprockets projecting laterally from said machine 15 and engaging with said loop, and means for preventing breakage of said chain on tilting of said machine including a member moved automatically, independently of the tension of said chain, relative to said machine on tilting of the latter.

33. In a mining apparatus, a wheeled truck, a mining machine thereon, said machine comprising a body and a plane pivoted cutter bar adjustable bodily relative to 25 said machine and also mounted for swinging movement in its own plane, a flexible truck driving connection between said mining machine and a wheel of said truck, means for tilting said body on said truck to give said 30 bar an upward or downward inclination, and slack-control means cooperating with said flexible connection moving in predetermined relation with said last mentioned means.

35. 34. In a mining apparatus, a wheeled truck frame, a mining machine pivotally supported on said truck frame, a flexible driving connection between said mining machine and truck wheel, means for tilting 40 said machine upon a frame including a horizontal shaft parallel to the axis of tilting and mounted on said frame, lever means secured to said shaft engaging the mining machine, lever means on said shaft for turning 45 ing the same, and lever means also carried by said shaft and carrying an idler element about which said flexible connection passes.

35. In a mining apparatus, a wheeled truck frame, a mining machine, pivotally supported on said truck frame, a flexible driving connection between said mining machine and a truck wheel, means for tilting said machine upon a frame including a horizontal shaft parallel to the axis of tilting 55 and mounted on said frame, lever means secured to said shaft engaging the mining machine, lever means on said shaft for turning the same, means carried on said machine for applying force to said lever, and lever means 60 also carried by said shaft and carrying an idler element about which said flexible connection passes.

36. In a mining apparatus, a wheeled truck frame, a mining machine pivotally supported on said truck frame, a flexible

driving connection between said mining machine and a truck wheel, means for tilting said machine upon a frame including a horizontal shaft parallel to the axis of tilting and mounted on said frame, lever means secured to said shaft engaging the mining machine, lever means on said shaft for turning the same, means carried on said machine for applying force to said lever, said last mentioned means comprising a screw operatively connected to said lever and a manually rotatable nut carried by said machine, and lever means also carried by said shaft and carrying an idler element about which said flexible connection passes.

37. In a mining apparatus, a wheeled truck frame, a mining machine pivotally supported on said truck frame, a flexible driving connection between said mining machine and a truck wheel, means for tilting said machine upon a frame including a horizontal shaft parallel to the axis of tilting and mounted on said frame, lever means secured to said shaft engaging the mining machine, lever means on said shaft for turning the same, means carried on said machine for applying force to said lever, said last mentioned means comprising a screw operatively connected to said lever, a manually rotatable nut carried by said machine and ratchet mechanism for rotating the nut, and lever means also carried by said shaft and carrying an idler element about which said flexible connection passes.

38. In a mining machine including a cutter bar and a machine frame, a hollow shaft extending transversely of said frame, a pair of worm wheels rotatably mounted in coaxial relation to said shaft and between the ends of the latter, friction clutch means loadable to connect either of said worm wheels to said shaft, and friction clutch controlling means including a member accessible for operation from either end of said shaft and disposed within said shaft and means for loading said frictions controlled by the position of said member.

39. In a mining machine, a chain carrying cutter bar, actuating means therefor including a chain driving sprocket and a shaft coaxial therewith, and means for adjusting the bar rectilinearly by power through a series of parallel positions while said shaft remains parallel to a single straight line including cooperating adjusting means coaxial with said shaft.

40. In a mining machine, a chain carrying cutter bar, actuating means therefor including a chain driving sprocket and a shaft coaxial therewith, and means for adjusting said shaft and said bar by power through a series of parallel positions while said shaft remains parallel to a single straight line including cooperating means coaxial with said shaft.

41. In a mining machine, coaxial motor driven bar plane adjusting and bar actuating means.
42. In a mining machine, a bar, a machine frame, supporting means permitting bodily movement of said bar about a longitudinal axis and swing of said bar, and power means for actuating said bar and for adjusting a portion of said supporting means rectilinearly towards and from said axis including coaxial bar actuating and bar adjusting means.
43. In a mining machine, a bar, a machine frame, supporting means permitting bodily movement of said bar about a longitudinal axis and swing of said bar, and power means for actuating said bar and for adjusting a portion of said supporting means rectilinearly towards and from said axis including coaxial bar actuating and bar adjusting means rotatable on an axis perpendicular to the bar.
44. In a mining machine, a bar, a machine frame, supporting means permitting bodily movement of said bar about a longitudinal axis and swing of said bar, and power means for actuating said bar and for adjusting a portion of said supporting means rectilinearly towards and from said axis including coaxial bar actuating and bar adjusting means rotatable on an axis perpendicular to the bar and coincident with its axis of swing.
45. In a mining machine, a support, a cutter bar, and power means for actuating said bar, swinging the same about an axis perpendicular thereto, moving the same bodily about an axis perpendicular to said first mentioned axis, and moving the same rectilinearly towards and from said second mentioned axis while maintaining said first mentioned axis, during such rectilinear movement, parallel to a line parallel to it at the start of such movement, and means for tilting said support about a transverse axis.
46. In a mining machine, a cutter bar, actuating means therefor including a driving shaft, and means for adjusting the same and said bar rectilinearly by power to different positions parallel to lines parallel to their original positions including means coaxial with said shaft and cooperating therewith to effect such adjustment.
47. In a mining machine, a chain carrying cutter bar, actuating means therefor including a chain driving sprocket and a shaft coaxial therewith, and means for adjusting the bar rectilinearly by power through a series of parallel positions including coacting adjusting means coaxial with said shaft and cooperating therewith to effect such adjustment.
48. In a mining machine, a chain carrying cutter bar, actuating means therefor including a chain driving sprocket and a shaft coaxial therewith, and means for adjusting said shaft and said bar by power rectilinearly through a series of parallel positions including means coaxial with said shaft and cooperating therewith to effect such adjustments.
49. In a mining apparatus, coaxial motor driven cutting mechanism adjusting and actuating means.
50. In a mining machine, a motor, a neck, cutting mechanism supported thereby and adjustable rectilinearly in a radial direction towards and from the axis of said neck, said cutting mechanism including orbitally movable cutting elements whose orbit maintains, during rectilinear radial adjustment of the cutting mechanism, a uniform angular relation to the direction of such adjustment, means for effecting orbital movement of said cutting elements, and means driven by said motor for effecting such adjustment including a member rotatable on an axis perpendicular to the axis of said neck.
51. In a mining machine, cutting mechanism, a screw perpendicular thereto and constituting actuating means therefor, a neck, members cooperating with said screw to support and at the will of the operator move said cutting mechanism at right angles to and towards and from the axial line of the neck, and means extending through said neck for transmitting power to said screw.
52. In a mining machine, cutting mechanism, a screw perpendicular thereto and constituting actuating means therefor, a neck, members cooperating with said screw to support and at the will of the operator move said cutting mechanism at right angles to and towards and from the axial line of the neck, and means extending through said neck and coaxial with the axis thereof for transmitting power to said screw.
53. In a mining machine, a support, cutting mechanism including orbitally movable cutting elements, a screw perpendicular thereto and constituting actuating mechanism therefor for effecting orbital movement of said cutting elements, members cooperating with said screw to support and at the will of the operator move said cutting mechanism in either direction in a path parallel to the axis of said screw, and swinging means for said cutting mechanism movable therewith during its movements in such path.
54. In a mining machine, a support, cutting mechanism including orbitally movable cutting elements, a screw perpendicular thereto and constituting actuating mechanism therefor for effecting orbital movement of said cutting elements, members cooperating with said screw to support and at the will of the operator move said cutting mechanism in either direction in a path parallel to the axis of said screw, and swinging means for said cutting mechanism actuated by said screw and movable with said cutting

mechanism during its movements in such paths.

55. In a mining machine, a support cutting mechanism, a screw perpendicular thereto and constituting actuating mechanism therefor, members cooperating with said screw to support and at the will of the operator move said cutting mechanism and screw in either direction in a path parallel to the axis of said screw, and swinging means for said cutting mechanism movable therewith during its movements in such path.

56. In a mining machine, a support, cutting mechanism, a screw perpendicular thereto and constituting actuating mechanism therefor, members cooperating with said screw to support and at the will of the operator move said cutting mechanism and screw in either direction in a path parallel to the axis of said screw, and swinging means for said cutting mechanism actuated by said screw and movable with said cutting mechanism during its movements in such paths.

57. In a mining machine, cutting mechanism, a screw perpendicular thereto and constituting actuating means therefor, a neck, members cooperating with said screw to support and at the will of the operator move said cutting mechanism at right angles to and towards and from the axis of said neck, means for rotating said neck, and swinging means for said cutting mechanism movable therewith during its movement towards and from the neck axis.

58. In a mining machine, cutting mechanism, a screw perpendicular thereto and constituting actuating means therefor, a neck, members cooperating with said screw to support and at the will of the operator move said cutting mechanism at right angles to and towards and from the axis of said neck, means for rotating said neck, and swinging means for said cutting mechanism actuated by said screw movable therewith during its movements towards and from the neck axis.

59. In a mining machine, cutting mechanism, a screw perpendicular thereto and constituting actuating means therefore, a neck, members cooperating with said screw to support and at the will of the operator move said cutting mechanism and screw at right angles to and towards and from the axis of said neck, and swinging means for said cutting mechanism movable therewith during its movement towards and from the neck axis.

60. In a mining machine, cutting mechanism, a screw perpendicular thereto and constituting actuating means therefor, a neck, members cooperating with said screw to support and at the will of the operator move said cutting mechanism and screw at right

angles to and towards and from the axis of said neck, means for rotating said neck, and swinging means for said cutting mechanism actuated by said screw movable therewith during its movements towards and from the neck axis.

61. In a mining machine, cutting mechanism, mutually engaging screw and nut elements, driving connections between one of said elements and said cutting mechanism, means for rotating the other of said elements, and means for selectively connecting the first element to the second for rotation therewith or holding the same against rotation.

62. In a mining machine, cutting mechanism, mutually engaging screw and nut elements, driving connections between one of said elements and said cutting mechanism, and means for rotating said elements simultaneously or one while the other remains stationary.

63. In a mining machine, a cutter bar provided with orbitally movable cutting elements, a single member rotatable on an axis perpendicular thereto and constituting means for transmitting power to said cutting elements to cause orbital movement thereof, and means adapted to cooperate directly with said member at the will of an operator to effect movement thereof and of said bar by power rectilinearly in the direction in which said member extends.

64. In a mining machine, a cutter bar provided with orbitally movable cutting elements guided in a plane orbit, a member rotatable on an axis perpendicular to the plane of said orbit and constituting means for transmitting power to said cutting elements to cause orbital movement thereof, said member being rotatable on an axis in a line intersecting the plane of the orbit of said cutting elements within the orbit, and means adapted to cooperate directly with said member at the will of an operator to move said bar by power rectilinearly in the direction in which said member extends while the orbit of the cutting elements remains constantly parallel to a plane perpendicular to said direction of rectilinear movement.

65. In a mining machine, a cutter bar provided with orbitally movable cutting elements, a member rotatable on an axis perpendicular thereto and constituting means for transmitting power to said cutting elements to cause orbital movement thereof, said member being rotatable on an axis in a line intersecting the plane of the orbit of said cutting elements within the orbit, and means adapted to cooperate directly with said member at the will of an operator to effect movement thereof and of said bar by power rectilinearly in the direction in which said member extends.

66. In a mining machine, a cutter bar,

actuating means therefor including a driving shaft, and means for adjusting the bar by power to different parallel positions including cooperating means coaxial with said shaft, one of said means being arranged to hold said shaft against rotation to effect such adjustment.

67. In a mining machine, a motor, a cutter bar, actuating means therefor driven by said motor including a driving shaft, and means for adjusting the same and said bar rectilinearly by power to different positions parallel to lines parallel to their original positions including cooperating adjusting means coaxial with said shaft.

68. In a mining machine, a cutter bar, and bar supporting and adjusting means including a member rotatable at all times when said bar is actuated, and a cooperating member arranged to be held stationary to effect bar adjustment, and means cooperating directly with said first mentioned member to support and adjust said cutter bar by power.

69. In a mining machine, coaxial power operated bar plane adjusting and bar actuating means, said means being alternatively operable.

70. In a mining machine, a cutter bar, actuating means therefor including a driving shaft, and means for adjusting said bar by power to different parallel positions including cooperating means coaxial with said shaft, said coaxial means including an element arranged to be held stationary to effect such adjustment.

71. In a mining machine, a plane cutter bar, actuating means therefor including a final driving shaft, and means for adjusting said bar rectilinearly by power to different parallel positions to which it remains parallel during its adjustment including coacting adjusting means coaxial with said shaft and cooperating therewith to effect such adjustment.

72. In a mining machine, a cutter bar having orbitally movable cutting elements movable in a plane orbit, actuating means therefor including a driving shaft disposed on an axis in a line intersecting the plane of the orbit of said cutting elements within the orbit, and means for adjusting said bar rectilinearly by power to different parallel positions to which it remains parallel during its adjustment including coacting adjusting means coaxial with said shaft and cooperating directly therewith to effect such adjustment.

73. In a mining apparatus, coaxial power operated cutting mechanism adjusting and actuating means, said means being alternatively operable.

74. In a mining machine, a motor, a cutter bar provided with orbitally movable cutting elements, mechanism driven by said motor including a member rotatable on an axis per-

pendicular thereto and constituting means for effecting orbital movement of said cutting elements, and means adapted to cooperate directly with said member at the will of an operator to effect movement thereof and of said bar by power rectilinearly in the direction in which said member extends.

75. In a mining machine, a portable base, kerf cutting mechanism mounted on said base including a cutter carrying head rotatable about a longitudinal axis and a pivoted kerf cutter mounted on said head for adjustment toward and from the head axis, and motor operated devices for adjusting said kerf cutter toward and from the head axis including cooperating screw and nut elements, and means for rotating one of said elements while the other is held against rotation.

76. In a mining machine, a portable base, kerf cutting mechanism mounted on said base including a cutter carrying head rotatable about a longitudinal axis and a pivoted kerf cutter mounted on said head for adjustment toward and from the head axis, and motor operated devices for adjusting said kerf cutter toward and from the head axis including cooperating screw and nut elements, and means for rotating said nut element while said screw is held against rotation.

77. In a mining machine, a portable base, kerf cutting mechanism mounted thereon including a cutter carrying head rotatable about a longitudinal axis, a guideway on said head arranged perpendicularly to said head axis and a pivoted kerf cutter mounted on said guideway for adjustment toward and from the head axis, and motor operated devices for adjusting said kerf cutter along said guideway toward and from the head axis including cooperating relatively rotatable screw and nut elements, and means for rotating one of said elements while the other is held against rotation.

78. In a mining machine, a portable base, kerf cutting mechanism mounted thereon including a cutter carrying head rotatable about a longitudinal axis, a guideway on said head arranged perpendicularly to said head axis and a pivoted kerf cutter mounted on said guideway for adjustment toward and from the head axis, and motor operated devices for adjusting said kerf cutter along said guideway toward and from the head axis including cooperating relatively rotatable screw and nut elements, means for rotating said nut element while said screw is held against rotation.

79. In a mining machine, a portable base, kerf cutting mechanism mounted on said base including a cutter carrying head rotatable about a longitudinal axis, a guideway on said head arranged perpendicularly to the head axis and a pivoted kerf cutter

mounted on said guideway for adjustment toward and from the head axis, a support on which said cutter head is mounted for rotation with respect thereto, a motor carried by said support, and devices operated by said motor for adjusting said kerf cutter rectilinearly along said guideway toward and from the head axis including relatively rotatable adjusting elements having their axes extending perpendicularly to the plane of swinging movement of said kerf cutter.

80. In a mining machine, a portable base, kerf cutting mechanism mounted on said base including a cutter carrying head rotatable about a longitudinal axis, a guideway on said head arranged perpendicularly to the head axis and a pivoted kerf cutter mounted on said guideway for adjustment toward and from the head axis, a support on which said cutter head is mounted for rotation with respect thereto, a motor carried by said support, devices operated by said motor for adjusting said kerf cutter rectilinearly along said guideway toward and from the head axis, and devices operated by said motor for rotating said cutter head relative to said support, said kerf cutter adjusting devices including relatively rotatable adjusting elements having their axes extending perpendicularly to the plane of swinging movement of said kerf cutter.

81. In a mining machine, a portable base, kerf cutting mechanism mounted on said base including a cutter carrying head rotatable about a longitudinal axis and a pivoted kerf cutter mounted on said head for adjustment toward and from the head axis, and motor operated devices for adjusting said kerf cutter toward and from the head axis including cooperating screw and nut elements, means for rotating one of said elements while the other is held against rotation, and motor operated devices for rotating said cutter head about its axis and for swinging said kerf cutter relative to said cutter head.

82. In a mining machine, a portable base, kerf cutting mechanism mounted on said base including a cutter carrying head rotatable about a longitudinal axis and a pivoted kerf cutter mounted on said head for adjustment toward and from the head axis, motor operated devices for adjusting said kerf cutter toward and from the head axis including cooperating screw and nut elements, means for rotating said nut element while said screw is held against rotation, and motor operated devices for rotating said cutter head about its axis and for swinging said kerf cutter relative to said cutter head.

83. In a mining machine, a portable base, kerf cutting mechanism mounted thereon including a cutter carrying head rotatable about a longitudinal axis, a guideway on said head arranged perpendicularly to said

head axis and a pivoted kerf cutter mounted on said guideway for adjustment toward and from the head axis, motor operated devices for adjusting said kerf cutter along said guideway toward and from the head axis including cooperating relatively rotatable screw and nut elements and means for rotating one of said elements while the other is held against rotation, and motor operated devices for rotating said cutter head about its axis and for swinging said kerf cutter relative to said cutter head.

84. In a mining machine, a portable base, kerf cutting mechanism mounted thereon including a cutter carrying head rotatable about a longitudinal axis, a guideway on said head arranged perpendicularly to said head axis and a pivoted kerf cutter mounted on said guideway for adjustment toward and from the head axis, motor operated devices for adjusting said kerf cutter along said guideway toward and from the head axis including cooperating relatively rotatable screw and nut elements and means for rotating said nut elements while said screw is held against rotation, and motor operated devices for rotating said cutter head about its axis and for swinging said kerf cutter relative to said cutter head.

85. In a mining machine, a portable base, a support mounted on the forward end of said base, a vertical guideway carried by said support and extending downwardly in advance of said base, a pivoted kerf cutter mounted on said guideway for adjustment vertically into parallel horizontal planes, and motor operated devices for adjusting said kerf cutter comprising cooperating screw and nut elements and means for rotating one of said elements while the other is held against rotation.

86. In a mining machine, a portable base, a support mounted on the forward end of said base, a vertical guideway carried by said support and extending downwardly in advance of said base, a pivoted kerf cutter mounted on said guideway for adjustment vertically into parallel horizontal planes, and motor operated devices for adjusting said kerf cutter comprising cooperating screw and nut elements and means for rotating said nut element while said screw is held against rotation.

87. In a mining machine, a portable base, a support mounted on the forward end of said base, a vertical guideway carried by said support, a pivoted kerf cutter mounted on said guideway for adjustment therealong vertically into parallel horizontal planes, and motor operated devices for adjusting said kerf cutter into aforesaid parallel planes including relatively rotatable screw and nut elements having their axes alined with the pivotal axis of said kerf cutter.

88. In a mining machine, a portable base,

a support mounted on the forward end of said base, a vertical guideway carried by said support extending downwardly in advance of said base, a pivoted kerf cutter mounted on said guideway for adjustment therealong vertically into parallel horizontal planes, and motor operated devices for adjusting said kerf cutter into aforesaid parallel planes including relatively rotatable screw and nut elements having their axes extending perpendicularly to the plane of swinging movement of said kerf cutter.

89. In a mining machine, a portable base, a support mounted on the forward end of said base, a vertical guideway carried by said support, a pivoted kerf cutter mounted on said guideway for adjustment therealong vertically into parallel horizontal planes, motor operated devices for adjusting said kerf cutter into aforesaid parallel planes including relatively rotatable screw and nut elements having their axes alined with the pivotal axis of said kerf cutter and means for rotating one of said elements while the other is held against rotation.

90. In a mining machine, a wheeled truck adapted to travel along a mine trackway, a support pivotally mounted on said truck to rock relative thereto about a transverse axis, a vertical guideway carried at the forward end of said support and extending downwardly therefrom towards the mine bottom, a pivoted kerf cutter mounted on said guideway for adjustment rectilinearly therealong vertically into parallel horizontal planes, motor operated devices carried by said support for adjusting said kerf cutter into aforesaid parallel planes, and motor operated devices for moving said kerf cutter bodily longitudinally of the trackway at a cutting speed with the tip of said kerf cutter moving in lines parallel to the trackway whether or not said support is tilted about said transverse axis.

45 91. In a mining machine, a wheeled truck adapted to travel along a mine trackway, a support pivotally mounted on said truck to rock relative thereto about a transverse axis, a vertical guideway carried at the forward end of said support, a pivoted kerf cutter mounted on said guideway for adjustment therealong vertically into parallel horizontal planes, and motor operated devices carried by said support for adjusting said kerf cutter into aforesaid parallel planes comprising cooperating relatively rotatable screw and nut elements arranged perpendicularly to the plane of swinging movement of said kerf cutter.

60 92. In a mining machine, a wheeled truck adapted to travel along a mine trackway, a support pivotally mounted on said truck to rock relative thereto about a transverse axis, kerf cutting mechanism mounted on the forward end of said support in a position over-

hanging the truck and including a pivoted plane kerf cutter adjustable relative to said pivoted support rectilinearly into parallel horizontal planes while the plane of said cutter always remains parallel to said planes 70 and swingable about an axis located in advance of said truck, motor operated devices carried by said support for adjusting said kerf cutter into aforesaid parallel planes, and motor operated devices for moving said 75 kerf cutter bodily longitudinally of the trackway at a cutting speed with the tip of said bar moving in uniform space relation to the plane of the top of the trackway during a given bodily longitudinal movement as set 80 forth, whether or not said support is tilted about said transverse axis.

93. In a mining machine, a wheeled truck adapted to travel along a mine trackway, a support pivotally mounted on said truck to 85 rock relative thereto about a transverse axis, kerf cutting mechanism mounted on the forward end of said support including a vertical guideway extending downwardly in advance of said truck, a frame slidably 90 mounted on said guideway and a pivoted kerf cutter carried by said frame, motor operated devices carried by said support for adjusting said kerf cutter rectilinearly along said guideway into parallel horizontal 95 planes, and motor operated devices for moving said kerf cutter longitudinally of the trackway at a cutting speed in a path parallel with the plane of the trackway irrespective of the tilted position of said support 100 about said transverse axis, whereby the lowermost portion of the kerf cut shall be parallel to a plane parallel to the top of the trackway.

94. In a mining machine, a wheeled truck 105 adapted to travel along a mine trackway, a support pivotally mounted on said truck to rock relative thereto about a transverse axis, devices at the rear end of said truck for tilting said support about its axis relative to 110 said truck, kerf cutting mechanism mounted on the forward end of said support including a vertical guideway extending downwardly in advance of said truck and a pivoted kerf cutter adjustable rectilinearly 115 along said guideway into parallel horizontal planes, and motor operated devices carried by said support for adjusting said kerf cutter along said guideway into aforesaid parallel planes comprising relatively rotatable 120 screw and nut elements.

95. In a mining machine, a wheeled truck adapted to travel along a mine trackway, a support pivotally mounted on said truck to rock relative thereto about a transverse axis, 125 devices at the rear end of said truck for tilting said support about its axis relative to said truck, kerf cutting mechanism mounted on the forward end of said support including a vertical guideway extending downwardly 130

- in advance of said truck and a pivoted kerf cutter adjustable rectilinearly along said guideway into parallel horizontal planes, and motor operated devices carried by said support for adjusting said kerf cutter along said guideway into aforesaid parallel planes comprising a screw adjustable axially with said kerf cutter and a rotatable nut engaging said screw. 5
96. In a mining machine, a wheeled truck adapted to travel along a mine trackway, a support pivotally mounted on said truck to rock relative thereto about a transverse axis, devices at the rear end of said truck for tilting said support about its axis relative to said truck, kerf cutting mechanism mounted on the forward end of said support including a vertical guideway extending downwardly in advance of said truck and a pivoted kerf cutter adjustable rectilinearly along said guideway into parallel horizontal planes, and motor operated devices carried by said support for adjusting said kerf cutter along said guideway into aforesaid parallel planes comprising a screw adjustable axially with said kerf cutter, a rotatable nut engaging said screw, and means for holding said screw against rotation during rotation of said nut to effect axial adjustment of said screw. 10
97. In a mining machine, a wheeled truck adapted to travel along a mine trackway, a support mounted on said truck, a motor carried by said support stationary with respect thereto and having its power shaft horizontally disposed and extending longitudinally of the machine, kerf cutting mechanism carried by said support including a cutter head rotatable relative to said support about a longitudinal axis, a guideway carried by said cutter head arranged perpendicularly to the cutter head axis and extending downwardly therefrom towards the mine bottom and a pivoted kerf cutter mounted on said guideway for adjustment rectilinearly therealong toward and from the head axis, devices driven by said motor for adjusting said kerf cutter along said guideway toward and from the head axis, devices driven by said motor for rotating the cutter head about its axis relative to said support while said motor remains stationary, and devices driven by said motor for driving the truck wheels to propel the apparatus along the mine trackway. 15
98. In a mining machine, a wheeled truck adapted to travel along a mine trackway, a support mounted on said truck, a motor carried by said support stationary with respect thereto and having its power shaft horizontally disposed and extending longitudinally of the machine, kerf cutting mechanism carried by said support including a cutter head rotatable relative to said support about a longitudinal axis, a guideway carried by said cutter head arranged perpendicularly to the cutter head axis, and a pivoted kerf cutter mounted on said guideway for adjustment rectilinearly therealong toward and from the head axis and including relatively rotatable adjusting elements having their axes extending parallel with said guideway. 20
99. In a mining machine, a wheeled truck adapted to travel along a mine trackway, a support mounted on said truck, a motor carried by said support stationary with respect thereto and having its power shaft horizontally disposed and extending longitudinally of the machine, kerf cutting mechanism carried by said support including a cutter head overhanging said truck and rotatable relative to said support about a longitudinal axis, a guideway carried by said cutter head arranged perpendicularly to the cutter head axis and extending downwardly therefrom towards the mine bottom and a pivoted kerf cutter mounted on said guideway for adjustment rectilinearly therealong toward and from the head axis, devices driven by said motor for adjusting said kerf cutter along said guideway toward and from the head axis, devices driven by said motor for rotating the cutter head about its axis relative to said support while said motor remains stationary, and devices driven by said motor for driving the truck wheels to propel the apparatus along the mine trackway. 25
100. In a mining machine, a wheeled truck adapted to travel along a mine trackway, kerf cutting mechanism mounted on said truck including a cutter head rotatable about a longitudinal axis, a guideway carried by said cutter head arranged perpendicularly to the head axis and a pivoted kerf cutter mounted on said guideway for adjustment rectilinearly therealong toward and from the head axis, motor operated devices for adjusting said kerf cutter along said guideway, and motor operated devices for driving the truck wheels to propel the apparatus bodily along the mine trackway to effect sumping and withdrawal movements of said kerf cutter, said kerf cutter adjusting devices including relatively rotatable adjusting elements having their axes extending parallel with said guideway. 30
101. In a mining machine, a wheeled support, a frame member pivotally connected with said support to rock on a transverse axis, a second frame member pivotally connected to the first frame member to rock on a longitudinal axis, plane cutting mechanism mounted on said second frame and overhanging said wheeled support, said cutting mechanism having angular movement with respect thereto about an axis located in advance of said wheeled support, means for rectilinearly raising and lowering said 35

cutting mechanism relative to said pivoted frame member while the plane of said cutting mechanism always remains parallel to a common plane, and motor operated devices 5 for moving said cutting mechanism at a cutting speed in a longitudinal direction along a path parallel to the plane of the surface over which the machine moves irrespective of the tilted position of said first 10 frame member about said transverse axis.

102. In a mining machine, a wheeled support, a frame member pivotally connected with said support to rock on a transverse axis, a second frame member pivotally connected to the first frame member at the front end thereof to rock on a longitudinal axis, a support mounted on said second frame member in a position overhanging said wheeled support and having angular movement 15 with respect thereto about an axis located in advance of said wheeled support, plane cutting mechanism mounted on said support and movable angularly therewith, means for raising and lowering said second 20 support relative to said pivoted frame member to effect rectilinear adjustment of said cutting mechanism while the plane of said cutting mechanism always remains parallel to a common plane, and motor operated devices 25 for moving the machine at a cutting speed longitudinally in a path parallel to the plane of the surface over which the machine moves irrespective of the tilted position 30 of said first frame member about said transverse axis.

103. In a mining machine, a wheeled truck adapted to travel along a mine trackway, a support pivotally mounted on said truck to rock relative thereto about a transverse axis, a vertical guideway carried at the forward end of said support, a pivoted kerf cutter mounted on said guideway for adjustment rectilinearly therealong vertically into parallel horizontal planes, and motor 40 operated devices carried by said support for adjusting said kerf cutter into aforesaid parallel planes including relatively rotatable adjusting elements having their axes extending parallel with said guideway.

104. In a mining machine, a wheeled truck adapted to travel along a mine trackway, a support pivotally mounted on said truck to rock relative thereto about a transverse axis, kerf cutting mechanism mounted 50 on the forward end of said support including a pivoted kerf cutter adjustable rectilinearly into parallel horizontal planes, and motor operated devices carried by said support for adjusting said kerf cutter into aforesaid parallel planes and including relatively rotatable adjusting elements cooperating 55 on relative rotation to effect bodily rectilinear axial movement of one of them

60 and having their axes extending perpen- 65 dicularly to the plane of swinging movement of said kerf cutter.

105. In a mining machine, a wheeled truck adapted to travel along a mine trackway, a support pivotally mounted on said truck to rock relative thereto about a transverse axis, kerf cutting mechanism mounted on the forward end of said support including a vertical guideway extending downwardly in advance of said truck, a frame slidably mounted on said guideway and a pivoted kerf cutter carried by said frame, and motor operated devices carried by said support for adjusting said kerf cutter rectilinearly along said guideway into parallel horizontal planes and including relatively rotatable adjusting elements having their axes extending parallel with said guideway. 70

106. In a mining machine, a wheeled truck adapted to travel along a mine trackway, a support pivotally mounted on said truck to rock relative thereto about a transverse axis, a vertical guideway carried at the forward end of said support in a position in advance of said truck and extending downwardly therefrom towards the mine bottom, a pivoted kerf cutter mounted on said guideway for adjustment rectilinearly therealong vertically into parallel horizontal planes, motor operated devices carried by said support for adjusting said kerf cutter into aforesaid parallel planes, and motor operated devices for driving the truck wheels to propel the machine bodily along the mine trackway to effect sumping and withdrawal movements of said kerf cutter. 75

107. In a mining machine, a wheeled truck adapted to travel along a mine trackway, a support pivotally mounted on said truck to rock relative thereto about a transverse axis, kerf cutting mechanism mounted on the forward end of said support in a position overhanging said truck and including a pivoted plane kerf cutter adjustable rectilinearly into parallel horizontal planes while the plane of said cutter always remains parallel to said planes and swingable about an axis located in advance of said truck, motor operated devices carried by said support for adjusting said kerf cutter into aforesaid parallel planes, and motor operated devices for driving the truck wheels to propel the machine bodily along the mine trackway to effect sumping and withdrawal movements of said kerf cutter. 80

108. In a mining machine, a wheeled truck adapted to travel along a mine trackway, a support pivotally mounted on said truck to rock relative thereto about a transverse axis, kerf cutting mechanism mounted on the forward end of said support including a vertical guideway extending downwardly in advance of said truck, a frame slidably mounted on said guideway and a pivoted kerf cutter carried by said frame, motor operated devices carried by said support for adjusting said kerf cutter into aforesaid parallel planes, and motor operated devices for driving the truck wheels to propel the machine bodily along the mine trackway to effect sumping and withdrawal movements of said kerf cutter. 85

109. In a mining machine, a wheeled truck adapted to travel along a mine trackway, a support pivotally mounted on said truck to rock relative thereto about a transverse axis, kerf cutting mechanism mounted on the forward end of said support including a vertical guideway extending downwardly in advance of said truck, a frame slidably mounted on said guideway and a pivoted kerf cutter carried by said frame, motor operated devices carried by said support for adjusting said kerf cutter into aforesaid parallel planes, and motor operated devices for driving the truck wheels to propel the machine bodily along the mine trackway to effect sumping and withdrawal movements of said kerf cutter. 90

110. In a mining machine, a wheeled truck adapted to travel along a mine trackway, a support pivotally mounted on said truck to rock relative thereto about a transverse axis, kerf cutting mechanism mounted on the forward end of said support including a vertical guideway extending downwardly in advance of said truck, a frame slidably mounted on said guideway and a pivoted kerf cutter carried by said frame, motor operated devices carried by said support for adjusting said kerf cutter into aforesaid parallel planes, and motor operated devices for driving the truck wheels to propel the machine bodily along the mine trackway to effect sumping and withdrawal movements of said kerf cutter. 95

111. In a mining machine, a wheeled truck adapted to travel along a mine trackway, a support pivotally mounted on said truck to rock relative thereto about a transverse axis, kerf cutting mechanism mounted on the forward end of said support including a vertical guideway extending downwardly in advance of said truck, a frame slidably mounted on said guideway and a pivoted kerf cutter carried by said frame, motor operated devices carried by said support for adjusting said kerf cutter into aforesaid parallel planes, and motor operated devices for driving the truck wheels to propel the machine bodily along the mine trackway to effect sumping and withdrawal movements of said kerf cutter. 100

112. In a mining machine, a wheeled truck adapted to travel along a mine trackway, a support pivotally mounted on said truck to rock relative thereto about a transverse axis, kerf cutting mechanism mounted on the forward end of said support including a vertical guideway extending downwardly in advance of said truck, a frame slidably mounted on said guideway and a pivoted kerf cutter carried by said frame, motor operated devices carried by said support for adjusting said kerf cutter into aforesaid parallel planes, and motor operated devices for driving the truck wheels to propel the machine bodily along the mine trackway to effect sumping and withdrawal movements of said kerf cutter. 105

113. In a mining machine, a wheeled truck adapted to travel along a mine trackway, a support pivotally mounted on said truck to rock relative thereto about a transverse axis, kerf cutting mechanism mounted on the forward end of said support including a vertical guideway extending downwardly in advance of said truck, a frame slidably mounted on said guideway and a pivoted kerf cutter carried by said frame, motor operated devices carried by said support for adjusting said kerf cutter into aforesaid parallel planes, and motor operated devices for driving the truck wheels to propel the machine bodily along the mine trackway to effect sumping and withdrawal movements of said kerf cutter. 110

114. In a mining machine, a wheeled truck adapted to travel along a mine trackway, a support pivotally mounted on said truck to rock relative thereto about a transverse axis, kerf cutting mechanism mounted on the forward end of said support including a vertical guideway extending downwardly in advance of said truck, a frame slidably mounted on said guideway and a pivoted kerf cutter carried by said frame, motor operated devices carried by said support for adjusting said kerf cutter into aforesaid parallel planes, and motor operated devices for driving the truck wheels to propel the machine bodily along the mine trackway to effect sumping and withdrawal movements of said kerf cutter. 115

115. In a mining machine, a wheeled truck adapted to travel along a mine trackway, a support pivotally mounted on said truck to rock relative thereto about a transverse axis, kerf cutting mechanism mounted on the forward end of said support including a vertical guideway extending downwardly in advance of said truck, a frame slidably mounted on said guideway and a pivoted kerf cutter carried by said frame, motor operated devices carried by said support for adjusting said kerf cutter into aforesaid parallel planes, and motor operated devices for driving the truck wheels to propel the machine bodily along the mine trackway to effect sumping and withdrawal movements of said kerf cutter. 120

116. In a mining machine, a wheeled truck adapted to travel along a mine trackway, a support pivotally mounted on said truck to rock relative thereto about a transverse axis, kerf cutting mechanism mounted on the forward end of said support including a vertical guideway extending downwardly in advance of said truck, a frame slidably mounted on said guideway and a pivoted kerf cutter carried by said frame, motor operated devices carried by said support for adjusting said kerf cutter into aforesaid parallel planes, and motor operated devices for driving the truck wheels to propel the machine bodily along the mine trackway to effect sumping and withdrawal movements of said kerf cutter. 125

devices carried by said support for adjusting said kerf cutter rectilinearly along said guideway into parallel horizontal planes, and motor operated devices for driving the 5 truck wheels to propel the machine bodily along the mine trackway to effect sumping and withdrawal movements of said kerf cutter.

109. In a mining machine, a wheeled support, a frame member pivotally connected with said support to rock on a transverse axis, a second frame member pivotally connected to the first frame member to rock on a longitudinal axis, plane cutting mechanism 10 mounted on said second frame in a position overhanging said wheeled support and having angular movement with respect thereto about an axis located in advance of said wheeled support, means for rectilinearly 15 raising and lowering said cutting mechanism relative to said pivoted frame member while the plane of said cutting mechanism always remains parallel to a common plane, and mechanism for driving the support wheels 20 to propel the machine bodily along the mine trackway to effect sumping and withdrawal movements of said cutting mechanism. 25

110. In a mining machine, a wheeled support, a frame member pivotally connected with said support to rock on a transverse axis, a second frame member pivotally connected to the first frame member at the front end thereof to rock on a longitudinal axis, a support mounted on said second frame member in a position overhanging said wheeled support and having angular movement with respect thereto, plane cutting mechanism mounted on said support and movable angularly therewith about an axis 35 located in advance of said wheeled support, means for raising and lowering said second support relative to said pivoted frame member to effect rectilinear adjustment of said cutting mechanism while the plane of said 40 cutting mechanism always remains parallel to a common plane, and mechanism for driving the support wheels to propel the machine bodily along the mine trackway to effect sumping and withdrawal movements 45 of said cutting mechanism.

111. In a mining machine, a frame, a motor thereon, an adjustable kerf cutting mechanism mounted on said frame including a plane kerf cutter adjustable into different parallel positions relative to said frame and driven by said motor, and devices driven by said motor for adjusting said kerf cutter including relatively rotatable screw and nut elements arranged with their axes extending perpendicularly to the plane of the kerf cutter, said screw element being movable axially with said kerf cutter during such adjustment.

112. In a mining machine, a frame, a motor thereon, vertical guideways on the for-

ward end of said frame, an adjustable kerf cutting mechanism driven by said motor including a kerf cutter support movable vertically along said guideways and having a kerf cutter pivotally mounted thereon, and devices driven by said motor for adjusting said support including relatively rotatable screw and nut elements arranged with their axes extending perpendicularly to the plane of swinging movement of the kerf cutter, said screw element being connected to and movable axially with said support during adjustment thereof.

113. In a mining machine, a frame, a motor thereon, vertical guideways on the forward end of said frame, an adjustable kerf cutting mechanism driven by said motor including a kerf cutter support movable vertically along said guideways and having a kerf cutter pivotally mounted thereon, and devices driven by said motor for adjusting said support including relatively rotatable screw and nut elements arranged with their axes extending perpendicularly to the plane of swinging movement of the kerf cutter, said screw element being connected to and movable axially with said support during adjustment thereof and said nut element being rotatably mounted on said frame and rotatable by said motor to effect such axial adjustment of said screw element and while the latter is held against rotation.

114. In a machine of the class described, movable supporting means, a plane kerf cutter adjustable by movement exclusively perpendicular to the plane thereof into different parallel planes relative to said supporting means, a motor on said supporting means, means for adjusting and holding said cutter in adjusted position, and power transmitting means operative between said motor and said cutter in all adjusted positions of the latter, said adjusting and holding means and power transmitting means being concentrically arranged.

115. In a machine of the class described, movable supporting means, a kerf cutter adjustable relative to said supporting means, a motor on said supporting means, a torque shaft adjustable as to length operative between said motor and said cutter, and a screw and nut revoluble with said shaft and holding said shaft and therewith said cutter in adjusted position.

116. In a machine of the class described, movable supporting means, a kerf cutter adjustable relative to said supporting means, a motor on said supporting means, a torque shaft adjustable as to length operative between said motor and said cutter, a screw and nut revoluble with said shaft and holding said shaft and therewith said cutter in adjusted position, and means for restraining said screw against rotation 120

130

while the nut revolves to adjust said shaft and therewith said cutter.

117. In a mining machine, the combination with a supporting frame, of a kerf-cutter adjustable relatively thereto, means comprising an extensible torque shaft for driving said kerf-cutter, means comprising a screw and a nut for adjusting the length of said shaft, and means for effecting relative rotation of said screw and nut to secure adjustment of the position of kerf-cutter.

In testimony whereof I affix my signature.

MORRIS P. HOLMES.
